MAGAZINE FOR RUBBER ERASERS

Paul Erick Stamm, Endicott, N. Y.

Application August 7, 1933, Serial No. 684,054

3 Claims. (Cl. 120—36)

My invention relates to an improvement in magazines for rubber erasers, and by which the rubber eraser can be contained and adjusted for the uses to which it is put, and at the same time free from soiling by contact with the hand or by grease or from any other source; and it has for its object a means of producing at the same time a handle to support the rubber eraser and also to adjust it to a usable position in the handle from time to time as the use of the eraser goes on.

With these objects in view my invention consists in certain novel features of construction and arrangement of parts as will be hereinafter fully described and pointed out in the claims. Reference being had to the accompanying drawing in which:

Fig. 1 is a front view partly in cross section of my device.

Fig. 2 is a front view of part of my device.

Fig. 3 is an edge view in cross section of my device.

Fig. 4 is an enlarged front view of part of my device.

Fig. 5 is an enlarged edge view of a fragmentary part of my device.

The same reference characters denote like parts in each of the several figures of the drawing.

In carrying out my invention I have a tubular formation or member A and slidably mounted within the same I have a flat formation B consisting of two expanded resilient opposite sides 2, 2, spaced apart except at their lower end and integral with them a base 3 and having the two spaced apart upper heads 4, 4, flat in formation and projecting in a turned over outline formation at 3 and 5, as shown in Figs. 3 and 5, the side 4 projecting upward and outward with the end turned over inward and back upon the side 4 as shown in Fig. 5. Between the opposite sides 2, 2, I slidably insert the rubber eraser C, with its upper end projecting as at X, X. This upper end of the eraser C is in resilient contact with and pressed against by the bent and turned overhead formations 5, 5, mounted on the base 3 or flat formed holder, I have mounted the turn screw 6, having upon it the threaded surface 7. The formation 6 being projected from the turn handle shank 8 projection from the shoulder 9 which in turn is projected from the turn handle 10. The handle 10 is in circular formation 11, and on which I produce a milled outer surface 12; at the upper end of my device I have slidably mounted upon and surmounting the same the cover cap D, as a guard over the projected eraser point C.

In carrying out my invention, I first remove the cap D from the member A, and enter the eraser C within the jaws of member B, slidably inserting the eraser C down between the resilient flat sides 4, 4, I then mount the member B within the tube A from uncoupling the screw handle 10 with its projection 6 from union with B and in this manner B can be slidably pushed down until the outward sloped sides are in pressure against the upper interior sides of the tube 10 A and thus form resilient pressure against the eraser member C and fix it at any convenient point for the extension of the eraser C, for erasing the interior flat, the eraser holder is thus slidably, fixedly mounted in tube A, the screw handle 10 coupled with the interior tube holder B; the distance provided by C adjusted by the screw movement of 12, and the movement is ready for that of an eraser. I then hold the eraser in the hand applying the eraser point C to the marks to be 20 erased from the paper. The cap D being removed during the operation when the use has ended, which is again mounted on the member A, and the invention placed in the pocket of the user. In the operation, and out of my device, I remove 25 cap D from the member body A, I then uncouple the handle section 6, 10 and 11 from the base of the interior holder B, I then pull B upward and outward from the top A, thus opening the resilient expanding jaws 5, 5 and the sides 4, 4, 4, and 30 insert between them the eraser member C extending the base downward between the jaws on sides 4, 4 until the point C is at a suitable distance extending out between 5, 5 of the sides 2, 2 for proper use; I then remount the holder B 35 within the tube A and move it downward within the tube A until the sides 2, 2 and jaws 5, 5 are in proper pressure against eraser C to be held to hold the eraser firmly for use, I then enter the screw member 6 in engagement with the base 40 3 and thus place the handle 12 in adjustable moving union with the member B for operating the eraser, vertical movement, all by means of the turn handle 12, and thus the device is ready to be applied to the paper surface for erasing marks 45 or general erasing purposes, and when the pointer C is worn down it can be moved upward in tube A by the repositioning of the turn handle placed in proper adjustment for further use. When not in use the cap D again mounted on the member 50 handle A and the device placed in the pocket for further use.

Having thus described my invention, what I claim as new, and for which I desire Letters Patent is as follows:

1. In an eraser holder, a tubular handle, an eraser clamping member inserted in one end of the handle, said eraser clamping member being formed from a single strip of resilient metal bent 5 upon itself into U-shaped formation, with the legs of the U-shaped formation having their free ends bent inwardly upon themselves to form enlargements between which an eraser is to be clamped, and means at the other end of the casing for advancing and retracting the clamping member.
2. In an eraser holder, a flat tubular handle open at both ends, eraser clamping means inserted in one end of the holder, enlargements on 10 the clamping member formed by bending portions 15

of the member upon themselves, a screw member associated with the clamping member and projecting through the other end of the casing, and means for engaging the screw to advance and retract the clamping member.

3. In an eraser holder, a flat tubular holder, eraser clamping means inserted in one end of the holder, enlargements on the clamping member formed by bending portions of the member upon themselves and toward each other for contacting the eraser element, a screw member carried by the clamping means and projecting through the holder, and means for engaging the screw to advance and retract the clamping member.

PAUL ERICK STAMM. 15
